UNITED STATES PATENT OFFICE.

WILLIAM F. HUTCHINSON, OF NYACK, NEW YORK, ASSIGNOR, BY MESNE ASSIGNMENTS, TO SECURITY MATCH COMPANY, OF HUDSON, NEW YORK, A CORPORATION OF NEW YORK.

MATCH-MACHINE.

SPECIFICATION forming part of Letters Patent No. 736,970, dated August 25, 1903.

Application filed November 7, 1902. Serial No. 130,392. (No model.)

To all whom it may concern:

Be it known that I, WILLIAM F. HUTCHINSON, of Nyack, Rockland county, New York, have invented certain new and useful Improvements in Match-Machines, of which the following is a full, clear, and exact description.

My invention relates to improvements in that class of match-machines which cut match-splints from strips of veneer that are arranged in parallel relation, and is an improvement over the machines shown in my United States Patents No. 668,519, of February 19, 1901, and No. 709,266, dated September 16, 1902.

My invention relates particularly to the device for cutting the splints and holding them in their parallel relation before they are punched into a frame or carrier, also to a device for simultaneously feeding the uncut veneer strips to the cutting mechanism, and also to the carriers holding the splints.

My invention further relates to a machine that simultaneously feeds the veneer strips to be cut into splints in parallel relation to one another, cuts these splints off successively, holds them while they are punched simultaneously into a frame or carrier, and then removes the cutting mechanism to allow the exit of the splints with the carrier.

With these ends in view my invention consists of certain features of construction and combinations of parts, which will be herein-after described and claimed.

Reference is to be had to the accompanying drawings, forming part of this specification, in which similar letters and figures of reference refer to similar parts throughout the several views.

Figure 1 is a side view of the machine, and Fig. 2 is an end view of the same. Fig. 3 is a top view of one end of the machine, illustrating the actuating mechanism of the feed. Fig. 4 is a section on the line 4-4 in Fig. 2, and Fig. 5 is a section on line 5-5 in Fig. 4, clearly illustrating the details of the cutting and feeding mechanism. Fig. 6 is a perspective view showing parts of the cutting device in section and fully illustrating their relative

positions. Fig. 7 is a section on line 7-7 in Fig. 2, which shows the method of fastening the plungers of the machine to the plunger-bar. Fig. 8 is a top view of the knife and front plate. Figs. 9 and 10 are longitudinal and cross sections, respectively, of one form of feeding device for feeding the veneer strips to the cutting mechanism. Fig. 11 is a view of the modified form of machine employing two knives.

Side frames 10, with the projecting tables 11 and the upper side pieces 12, form the main support for the machine. A shaft 13 is journaled in bearings in the frames 10, and a set of fast and loose pulleys 13^a is preferably employed to drive the same. This shaft 13 in turn drives, by means of gears or otherwise, the shaft 14, which has thereon a miter-gear 15, meshing with a similar gear 16 on a shaft 17, which runs longitudinally through the machine and is supported on its outer end in the bracket 17^a, which forms a bearing therefor.

On the extreme outer end of the shaft 17 is arranged a disk 18, acting as a crank for a link 19, which translates the circular motion of the disk to a rocking motion of an arm 20, which is adjustably arranged in a disk 21, so as to allow for a varying of the throw of the end of the arm. This disk 21 is on the end of the shaft 22, which is journaled in the bearings 23 and 24 and the standard 25, which will be apparent from Fig. 1. Arranged on the shaft 22 is another disk 26, having a similarly adjustably arranged lever 27, communicating, by means of a link 28, with a knife 29, this knife being integral with a plate 30 and being guided in the frame 31. It will thus be seen that this knife receives a reciprocatory motion across the machine, passing through an opening in the side frame 12.

The table 32 supports the veneer strips, and a set of guide-plates 32^a hold the veneer strips while they are being fed to the knife aforesaid and as will be seen from Figs. 4 and 6. A cross-bar secured to the back of the table 32 has fingers 33 arranged to project perpendicularly, forming between them spaces 34 for the reception of the veneer. The knife

passes between these fingers 33 and the guide-
plates 32^a, and the plate 30 passes in rear of
these fingers 33 and is held rigid by a frame-
work 35, that has an opening 36 therein to
5 facilitate the removal of splinters when oc-
casion demands, and a rib 31 on the face-
plate 30 runs in a slot in the lower part of the
frame 35, assisting in maintaining the posi-
tion of the plate. The frame 35 is supported
10 and secured to the side frames 12 by the arms
37. From this description it will be evident
that when the knife is at its extreme back-
ward position the veneer is free to be fed be-
tween the fingers 33 by a feeding mechanism,
15 to be described hereinafter, and then as the
knife is thrown across the machine, accom-
panied by the plate 30, the ends of these
strips are cut into splints, each occupying a
chamber formed by the fingers 33, the knife
20 29, and the plate 30. Arranged to recipro-
cate in these chambers are a set of plungers
38, secured to the plunger-arm 39 by means
of a plate 40, recessed to receive them, and
tightened by the bolt 41. The plunger-arm
25 is actuated by a connecting-rod 42 on either
side of the machine, this rod having a roller
43 (see Fig. 1) running in a slot on a cam 44.
These cams 44 are placed on the ends of the
shaft 14. The slots in the cams act to pull
30 down the plunger-rods and its plungers
on the completion of the forward stroke of the
knife while the splints are confined in the
chambers, as described above, thereby forcing
35 the splints from these chambers and into
the frame 67, having the cross-rods 68, which
may have serrations 69 on their adjoining
edges and which are supported on tracks 70,
which in turn are held up by the supports
71, running across the machine.
40 The bracket 17^a at the forward end of the
machine acts as a support for the side frames
10, at the same time holding the shaft 17, and
on its outer ends it has the blocks 45, guiding
a slide 46. This slide 46 is provided with a
45 roller 47, running in a slot 18^a in the disk 18
on the inner side of the disk. It will thus be
seen that the revolution of the disk while ac-
tuating the knife-throwing device also gives
50 to the slide 46 an intermittent reciprocatory
motion, which is communicated through the
turnbuckle 48 to the arm 49, which can be
slotted to receive one end of the turnbuckle,
so that its throw can be adjusted. This lever-
55 arm 49 actuates the arm 51, they being in-
gral and working loosely on the shaft 50; but
the lever-arm 51 has a pawl 52 secured thereto,
which actuates a ratchet 53, which is keyed
or otherwise secured to the shaft 50 and
causes a step-by-step rotation of the same.
60 Placed at convenient equidistant points
along the shaft 50, which is journaled in the
standards 54, are miter-gears 55, meshing
with similar gears 56, arranged on the cross-
rods 57. These cross-rods 57 are supported
65 in the bearings 58 on either side of the ma-
chine, (see Figs. 4 and 5,) which are secured

to the side frames 10, and immediately below
which are the bearings 63, arranged in slid-
able relation to the bearings 58, both being
clamped by the bolt 65, and the lower bear-
ings 63 being adjustable by reason of the slot
64 and the screw 66, and when the proper ad-
justment is secured a tightening of the bolts
65 and 66 hold the bearings in their adjusted
positions. The lower bearing operates to sup-
port cross-rods 72, and shafts 57 and 72 are
provided, respectively, with the gears 59 and
61, insuring their simultaneous revolution.
Adjacent to these gears are oppositely-ar-
ranged feed-wheels 60 and 62, being adapted
by means of the cut-away portions 60^a and
62^a, to embrace the rods 68 of the splint-hold-
ing frame, whereby it will be evident that an
intermittent rotation of these feed-wheels
will cause an intermittent advance of the
splint-carrying frames, the withdrawal of the
plate 30 allowing the exit of the splints, the
upper ends of which are still between the fin-
gers 33. The cross-rod 57 of the feeding mech-
anism is cut away, as shown in Fig. 5, to al-
low the advance splints to pass, in this case
the power being communicated entirely by
means of the lower rod 72; but in the case of
the other feeding mechanisms arranged in the
rear of the cutting device both the upper and
lower shafts can be run entirely across the
95 machine. On the rod 50 is arranged the mi-
ter-gear 73, (see Fig. 1,) which operates on a
miter-gear 74, which is on the short shaft with
the gear 75. The gear 75 operates a set of
gears 76 and 77, placed on the shafts 78 and
79, respectively, and the feed-rolls 80 and 81
are arranged on these shafts, as in Fig. 4, to
bear on the upper and lower edges of the ve-
neer strips to feed them forward, and these
rolls are preferably made of soft rubber or
similar elastic material to take up inequalities
in the edges of the veneer. These rods 78 and
79 can be journaled in suitable boxes 82,
working in the ways 83 and adjusted by means
of the screw 84, working through a plate 85,
that is held down to the side frame 12 by means
of the pivotal bolt and the thumb-screw 86.
In Figs. 9 and 10 I have set forth a modifica-
tion of this feeding mechanism, and in this
modified construction I employ two sheet-
metal disks, one on each side of each strip of
veneer, these disks being arranged on the
shaft 79 and held in their proper relation on
the shaft by the collars 88. These disks are
provided with the slots 89, thereby forming
the spring-arms 90. In the guide-plates 32^a,
approximately opposite the center of the shaft
79, I arrange the plates 91, between which
is placed a wedge 92, having a screw-threaded
120 perforation to receive the screws 93, that can
be turned by means of the heads 94. In this
way the plates 91 can be forced apart to any
desired extent. In the outer faces of these
plates 91 are arranged balls 95, that are held
125 in place by the spring action of the disks 87;
but strips may be employed for this purpose.

When a strip of veneer is placed between two disks 87 and the feeding mechanism is started, the wedges having been adjusted, the spring-plates 90 of the disks 87 are forced to engage each side of this veneer strip and feed it forward. When a plate 90 has passed the ball 95, or when a ball is not employed has passed the plate 91, its own spring action allows it to spring out of engagement with the veneer strip, and in this way no upward pull is exerted on the veneer. To illustrate this, I might say that in Fig. 9 a spring-plate in the position *a* would not be in engagement with the veneer strip, while spring-plates in the positions *b* and *c* by reason of the ball 95 would engage the strip. It will be obvious then that the only pressure exerted by the revolving disks will be in a forward direction. The faces of these disks 87 that are toward the veneer can be knurled or roughened, so that the contact with the veneer strip will be more positive.

In Fig. 11 I show a modification of the cutting mechanism, in which two knives 94 can be operated from opposite sides of the machine to meet in the center. These knives can be actuated by the levers 95 and 96, communicating through links 96^a to a disk 97 on a shaft 98, which receives its rocking motion by means of a roller 99 in the end of an arm thereon, this roller running in a slot in the cam 100; but of course it will be obvious that this particular kind of operating mechanism can be replaced by any mechanical equivalent to perform the same office; but I desire to emphasize the employment of two knives working toward one another to cut off the splints. I have found in practice that by having the knife successively engage the veneer strips but little power is required to run it, and, moreover, a more perfect splint results.

Having thus described my invention, what I claim as new, and desire to secure by Letters Patent, is—

1. A match-machine comprising a series of parallel guide-fingers, means for feeding veneer strips in parallel relation between the fingers, a knife moving to successively cut off the end of the strips into splints while in engagement with the fingers, and means for simultaneously forcing the splints into the carrier.

2. A match-machine comprising a series of parallel guide-fingers, means for feeding veneer strips between the fingers, a knife moving to successively sever the splints from the strips, a plate actuated by the knife to close the slots between the fingers, and means for

simultaneously punching the severed strips into the carrier.

3. A match-machine, comprising a series of parallel guide-fingers, means for feeding veneer strips between the fingers, a knife moving to successively sever the splints from the strips while the strips are engaged by the fingers, a plate carried by the knife adapted to move across the face of the fingers and successively close the slots between the fingers on the side opposite the knife, and means for simultaneously forcing the splints into the carrier.

4. A match-machine, comprising a carrier, a series of guide-fingers perpendicular to the carrier, means for feeding veneer strips between the fingers, a knife arranged to move across the machine in front of the guide-fingers to cut the splints from the strips, a plate carried by the knife to close the slots between the fingers, and means for forcing the splints into the carrier.

5. In a match-machine, the combination with a carrier, of four-wall guiding devices to guide the splints to the carrier, the front wall of such devices being successively made by the knife, and a plate carried by the knife to successively form the rear wall, the front and rear wall being movable so as to open a passage for the veneer and for the splints after they are engaged by the carrier.

6. A match-machine, comprising a series of fingers to receive the veneer strips between them, a knife arranged to cut transversely through the stock and along one side of the fingers to cut successive strips from the veneer strips, and a plate moving simultaneously with the knife and along the opposite side of the fingers so that the plate and knife between them hold the severed splints.

7. A match-machine, comprising a series of parallel fingers adapted to receive veneer or match-stock between them, a knife arranged to slide along one side of the fingers and cut successive splints from the veneer strips, a plate moving with the knife and along the opposite side of the fingers, and ejecting plungers moving downward between the fingers while the splints are held by the knife and plate.

In witness whereof I have hereunto set my hand to this specification in the presence of two subscribing witnesses.

WILLIAM F. HUTCHINSON.

In presence of—

W. B. HUTCHINSON,
J. G. DUNBAR.
